FILM VIEWER

Francis T. Coffey, Sr., Los Angeles, Calif.

Application November 14, 1950, Serial No. 12,989

Term of patent 14 years

(Cl. D61—1)

To all whom it may concern:

Be it known that I, Francis T. Coffey, Sr., a citizen of the United States, residing at Los Angeles, in the county of Los Angeles and State of California, have invented a new, original, and ornamental Design for a Film Viewer, of which the following is a specification, reference being had to the accompanying drawing, forming part thereof, in which:

Fig. 1 is a perspective view of the film viewer embodying my new design, the view being taken from the rear and operating side;

Fig. 2 is a side elevational view;

Fig. 3 is an end elevational view as observed in the direction of arrow 3 in Fig. 2;

Fig. 4 is an end elevational view as observed in the direction of arrow 4 in Fig. 2;

Fig. 5 is a top plan view; and

Fig. 6 is a perspective view, taken from the side opposite to that illustrated in Fig. 1 and showing the cover at said opposite side open, so as to disclose the interior of the viewer.

I claim:

The ornamental design for a film viewer, substantially as shown.

FRANCIS T. COFFEY, SR.
